UNITED STATES PATENT OFFICE

WILHELM TAMM, OF KIEL, GERMANY, ASSIGNOR, BY DIRECT AND MESNE ASSIGNMENTS, TO DEUTSCHE GASGLÜHLICHT-AUER-GESELLSCHAFT MIT BESCHRÄNKTER HAFTUNG, OF BERLIN, GERMANY, A CORPORATION OF GERMANY

BREATHING APPARATUS

Application filed April 11, 1928, Serial No. 269,249, and in Germany September 29, 1927.

It is known to remove the danger of the accumulation of nitrogen in breathing devices operated automatically by the lungs of the bearer by causing, while exhaling, a portion of the exhaled air to pass from the circulation system in the device into the open air by means of a so-called scavenging valve. The known scavenging valves are based on the principle that a valve will open a finely calibrated boring as soon as there is any super-pressure in the cycle of operation, and that the said boring will be closed when the pressure drops below the normal, so that a portion of the air in the device will pass into the atmosphere through said boring when the valve is open. Scavenging valves of this type show certain drawbacks, which are entirely removed by the present invention.

To make clearer the improvement over prior devices effected by the present invention, the drawbacks and sources of danger of the known scavenging valves will first be pointed out.

It is required unconditionally of a well working scavenging valve that it open at each exhalation and close tightly at each drawing in of air or oxygen. With the hitherto known scavenging valves operating automatically, there is available as motive power only the difference in pressure caused between the atmospheric pressure and that existing within the device by the resistance of the said device. When the breaths are small such differences of pressure may be extraordinarily small (+3 to 5 millimetres of water column). It is obvious that the construction of a valve which will have to be sensitive to such feeble forces, will give rise to considerable difficulties, and the supervision of such a valve will call for special attention. If for instance the loading spring of the scavenging valve is a little too strong, the said valve will not open at all at such small pressure differences. If, on the other hand, said spring is too weak, the valve will not close at pressures only slightly below normal, and in such case the scavenging will become delusive because, while at each exhaling a portion of the air from the device will pass into the atmosphere, during drawing

in air a corresponding quantity will flow back again. In scavenging valves provided with a rubber diaphragm the disadvantage exists, that the rubber will gradually grow hard, by which the elasticity of said diaphragm will decrease and larger pressures will be required for operating said valve. If a diaphragm of mica is used there is the danger to be reckoned with, that the inevitable condensation of water will cause the valve-disc to stick to its seat on account of the very high adhesion, so that while a high degree of tightness is obtained at a pressure below normal, there is a considerably greater amount of power required for opening it, which however is not available when the wearer is performing light work and consequently is breathing easily. A further danger exists in the fact that in all known scavenging valves the borings are very finely calibrated, and are more or less accessible from the outside, so that they might easily become choked through soot, dust or the like, rendering a faultless operation of the scavenging valve again impossible. In addition there will very easily be formed plugs caused by the condensate or saliva, in said boring, which might practically choke the valve, since a considerable pressure will be required to force said plugs out of the said borings.

All these drawbacks are obviated by the present invention, several embodiments of which are illustrated by way of example on the accompanying drawings. In said drawings,

Figure 1 shows diagrammatically the construction of a breathing device in accordance with the present invention.

Figure 1a shows a detail of Fig. 1.

Figures 2, 3, 4 and 5 show four additional modes of execution.

In all of the embodiments illustrated the operation of the scavenging valve is effected through an element which directly or indirectly closes the breathing cycle either totally or partially. In Figure 4 the valve disc *t* of the exhaling valve *a* is connected with the disc *b* of the scavenging valve *s* by means of the rod *c* in such a manner, that the scavenging valve *s* is closed when the breathing valve is

closed, but if the latter is opened the said scavenging valve *s* will also be opened.

In the modification shown in Figures 1 and 1a there is provided concentrically with the seat *d* of the exhaling valve *t* a second seat *e*, from which a pipe *f* leads to the calibrated boring *g* whose cross-sectional area is adjusted to control the amount of air discharged by the scavenging valve. As soon as the valve disc *t* opens during exhaling, the passage into the open air through the pipe *f* and the calibrated boring *g* is opened simultaneously, so that the necessary scavenging quantity can flow out. It will be understood that the resistance to the flow of air through the usual carbon dioxide absorbing cartridge is greater than through the pipe *f*, so that escape of a portion of the exhaled air through such pipe is insured.

The modification shown in Figures 2 and 3 are similar in principle to that shown in Figures 1 and 1a; only the arrangement of the valve is of different design. In the device according to Figure 2 the exhaled air flows through the pipe *h* against the rubber diaphragm *i*, which is jammed air-tight between the annular bodies *k* and *l* in such a manner, that it will close the concentrical valve seats *m* and *n* in its position of rest. In consequence of the exhaling pressure the diaphragm is lifted from the seats. The exhaled air flows between the said seats through the pipe *o*. That portion required for scavenging purposes flows simultaneously into the atmosphere through the pipe *f*. In Figure 3 there is provided in lieu of the movable diaphragm *i* a rigid valve disc *p*. As soon as a super-pressure is set up on the left side of the valve disc *p* owing to the exhalation, the said disc will be lifted from the two seats, permitting simultaneously the passage of the major portion of the exhaled air into the circulating system and the remaining portion into the pipe *f*.

In the modification shown in Figure 5 the operation of the scavenging valve *s* is effected by means of a special throttling member in the form of a disc *q*, which is connected with the scavenging valve *s* through a rod *c* guided in the bridge *r*. In the closed position of the scavenging valve *s* the disc *q* will either totally or partially close the cross-sectional area of the breathing duct. During exhalation the superpressure set up below the disc *q* will cause an axial rising of the disc *q* so that a larger cross-section is available for the passage of the exhaled air. At the same time the scavenging valve *s* is also opened to a corresponding extent. During stronger breathing, the axial displacement of the disc and in consequence the opening of the scavenging valve *s*, naturally will be increased. The larger quantity of air discharged into the atmosphere on heavy breathing is rendered necessary by the fact that increased breathing will

cause an increased consumption of oxygen, whereby the quantity of the nitrogen admitting with the oxygen and requiring to be removed will grow. In the known scavenging valves and also in those according to Figs. 1 to 4 the control of the quantity flowing out is effected automatically through the super-pressure set up in front of the scavenging opening, which pressure again is dependent on the breathing force, since for the passage of those portions of the circulating system situated behind the exhaling valve up to the bag, a drop of pressure is necessary, which will grow with increased breathing. But a device according to Figure 5 can be arranged directly in front of the breathing bag, so that no considerable variable super-pressure over the atmosphere is available for operating the scavenging valve, and consequently a different control of the scavenging quantity flowing off must be provided.

It is obvious, that in using a device according to Figure 5 the exhaling valve might perhaps be entirely dispensed with. With an unfavorable position of the exhaling valve it might prove necessary to substitute the scavenging valve according to Figure 5 for that shown in Figure 4. In the same way pipes *f* having a calibrated boring *g* according to Figure 1, may be connected to the scavenging valves according to Figures 4 and 5, and there may be effected other variations and combinations.

In arranging the pipe *f* and the calibrated boring *g* it is essential that the said boring *g* is situated at a safe place and that the pipe *f* lies within the region of influence of the cartridge in such a way, that the scavenging air flowing out will be raised in temperature on its passage to prevent condensation of moisture.

The present invention shows the following advantages over known scavenging valves:

As the scavenging valve is operated by a closing member for the circulating system, the opening of the scavenging valve at each exhalation is ensured. If the scavenging valve should not open, the closing member too would remain closed and the bearer of the device would experience an unsurmountable resistance when exhaling. Likewise a faultless closing of the scavenging valve is ensured. As this valve will open positively under any condition during the exhalation, the loading spring may be of such strength, that the said valve will close tightly during inhalation. The closing is furthermore assisted by the fact that the pressure below normal set up at the mouth piece will exist also at the closing member. The tight seat eventually is improved because after a few breaths condensate will collect at the scavenging valve, in consequence of which a water-seal is formed on the valve seat, which

will close any unsealed places which still might exist.

On account of the spatial separation of scavenging valve and calibrated scavenging boring it is possible to arrange the scavenging valve at any desired point in the breathing cycle, without fearing any choking. It is always possible to arrange the scavenging boring at a place which is protected against becoming dirty. The length and the form of the connection pipe is immaterial.

If the said connection pipe is arranged in such a manner that it lies within the region of influence of the cartridge, a further and highly essential advantage is obtained in view of the fact that the exhaling air is saturated with moisture at the moment of exhalation. The said air will cool down in a normal way during its passage to the cartridge, so that condensate will be separated out. As stated above such condensate can become dangerous if it passes into the scavenging boring. This danger is removed by the arrangement according to the invention in that the discharged air, flowing through the pipe *f*, will be raised in temperature in consequence of the raised temperature of the cartridge. As a result the capacity for absorbing water vapors up to the degree of saturation will increase, thereby not only preventing the condensation of vapor but vaporizing again and carrying off any condensate which might have flowed in. It is not necessary that the air continuously increase in temperature on its entire passage through the conduit *f*. When the conduit *f* is of sufficient cross-sectional area it will be sufficient, if the temperature rises in the last part from *f* to *g*.

I claim:

In a breathing apparatus having a closed breathing circuit adapted to be periodically scavenged to prevent the accumulation of nitrogen therein, the combination of a scavenging valve controlling a discharge conduit, and an exhaling valve arranged in said circuit and adapted to be moved by the pressure of the exhaled air, said valves being integrally connected in the form of a substantially flat disc.

In testimony whereof I affix my signature.
WILHELM TAMM.
